(57) **CLAIM**

The ornamental design for a vehicle exhaust trim, as shown and described.

DESCRIPTION

FIG. 1 is a top perspective view of a vehicle exhaust trim showing the new design in a first embodiment shown in a left-hand configuration.

FIG. 2 is a bottom perspective view thereof;

FIG. 3 is a top rear perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The claimed design includes a second embodiment of a vehicle exhaust trim, in a right-hand configuration, not illustrated because it is a mirror image of the embodiment shown.
